Attorney

UNITED STATES PATENT OFFICE.

ADELIA G. SHRAUGER, OF ODANAH, WISCONSIN.

JAR-LIFTER.

1,353,282.

Specification of Letters Patent. Patented Sept. 21, 1920.

Application filed September 25, 1919. Serial No. 326,341.

To all whom it may concern:

Be it known that I, ADELIA G. SHRAUGER, a citizen of the United States, residing at Odanah, in the county of Ashland and State 5 of Wisconsin, have invented certain new and useful Improvements in Jar-Lifters, of which the following is a specification.

My invention relates to new and useful improvements in jar lifters and has for its 10 principal object the construction of a device of this character in such a manner that it may be readily engaged with the jars so that the same may be lifted and moved from place to place.

15 Another object of the invention resides in the construction of the device in such a manner that it may be engaged with the jar while the same is immersed in hot liquid without touching the jar with the hand.

20 With these and other objects in view my invention consists in the novel details of construction and arrangement of parts which will be more clearly understood from the following specification and drawings in 25 which:

Figure 1 is a front elevation partly in section.

Fig. 2 is a side elevation.

30 Fig. 3 is a horizontal section on the line 3—3 of Fig. 1, and

Fig. 4 is a bottom plan.

In carrying out my invention I provide a bottom plate 1 which is preferably of the shape more particularly illustrated in Fig. 4 35 of the drawing and one edge of the plate, which I will hereafter term the rear edge, is provided with an up-turned flange 2 the purpose of which will be presently described. Eyes or staples 3 are secured to the under- 40 side of the plate and these eyes or staples are arranged in pairs so that each pair will be in alinement for a purpose to be later described.

A bail is indicated at 4 and is constructed 45 preferably from wire or a small rod which is bent to extend beneath the plate 1 and through one alining pair of eyes or staples 3. The wire bail 4 is bent to form the eyes 5, on each side, intermediate the ends, and 50 the wire is also bent so that the lower end 6 will extend at a slight angle to the handle and extend under the plate 1 adjacent the forward end thereof. A wire bail 7 is bent to extend under the plate 1, adjacent the 55 rear edge thereof, and through the alining pair of eyes or staples 3. The upper ends

of the bail 7 are formed with hooks 8 which are adapted to engage through the loops or eyes 5 formed on the bail. By the construction so far described it will be noted 60 that the bottom plate 1 is normally supported in a horizontal position through means of the angle extensions 6 on the bail 4 and the bail 7.

A ring or band 9 is provided on each 65 side with an eye or staple 10 which is adapted to be secured around or received in the loops or eyes 5. The ring or band 9 is thereby loosely connected to the bail so that it may be swung with respect to said bail. 70 This ring or band 9 may be of any desired size so as to fit the various shaped or sized jars.

From the above detailed description it is 75 thought that the advantages and manner of using my device will be clearly understood. My jar lifter is particularly adapted for lifting jars from hot liquid and conveying them to such a place as may be desired. It is also my object to provide a device 80 of this character which may be engaged with the jar without touching the jar with the hand. In Fig. 2 of the drawings I have illustrated the jar in dotted in lines and it will be seen in what position the several 85 parts will be when the jar is being lifted. When the jar is to be deposited the bail 4 is swung to the left and this in turn will slip the bottom plate 1 from beneath the jar and since the ring 9 is loosely secured to 90 the bail 4 this movement will allow the jar to remain in a vertical position. The bail can then be raised so that the ring or band 9 may be disengaged from the jar. When the jar is immersed in hot liquid and it is 95 desired to raise or lift the same the bail 4 is held in such a position that the ring or band 9 may be engaged over the jar. Then by pressing on the bail 4 to the right the front end of the plate 1 will be slipped be- 100 beneath the jar until the flange 2 engages the side of the jar. When this has been done the jar may be lifted and carried to such place as may be desired. The band 9 being loosely connected to the eye or loop 5 will 105 allow the proper swinging of the several parts whereby they may be engaged with the jar or disengaged therefrom.

The foregoing description and the drawings have reference to what may be considered the preferred, or approved form 110 of my invention. It is to be understood that

I may make such changes in construction and arrangement and combination of parts, materials, dimensions, etc., as may prove expedient and fall within the scope of the 5 appended claims.

Having fully described my invention what I claim as new and desire to secure by Letters Patent is:

- 10 1. A jar lifter comprising a plate, a bail pivotally connected to the plate, and a ring pivotally carried by the bail above the plate.
- 15 2. A jar lifter comprising a plate, having a flange formed on one edge thereof, a bail pivotally connected to the plate, and a band pivotally carried by the bail above the plate.
- 20 3. A jar lifter comprising a plate, a bail pivotally connected to the plate adjacent the forward end, a second bail connected to the first mentioned bail and pivotally connected to the plate adjacent the rear edge thereof, and a band pivotally carried by the first mentioned bail above the plate.
4. A jar lifter comprising a plate, a bail

pivotsally connected to the plate adjacent 25 the forward edge thereof, eyes formed on the bail intermediate the ends thereof, a second bail connected to the eyes and pivotally connected to the plate adjacent the rear edge thereof, and a band pivotally carried by 30 the eyes of said first mentioned bail.

5. A jar lifter comprising a plate, an upwardly extending flange formed on the rear edge of the plate, a bail pivotally connected to the plate adjacent the forward 35 edge thereof, eyes formed on the bail intermediate the ends thereof, a second bail connected to the eyes and pivotally connected to the plate adjacent the rear edge thereof, and a band pivotally carried by the 40 eyes of said first mentioned bail.

In testimony whereof I affix my signature in presence of two witnesses.

ADELIA G. SHRAUGER.
